United States Patent Office.

ROBERT W. TOWLE, OF SEARSPORT, MAINE.

Letters Patent No. 77,681, dated May 5, 1868

IMPROVED HANDLE FOR SMOOTHING-IRONS.

The Schedule referred to in these Letters Patent and making part of the same.

Be it known that I, ROBERT W. TOWLE, of Searsport, in the county of Waldo, and State of Maine, have invented a new and useful Removable and Replaceable Handle for Tailors' Press-Irons; and I do hereby declare that the following is a full, clear, and exact description of the construction and operation of the same, reference being had to the annexed drawings, making a part of this specification, in which—

Figure 1 is a perspective view of the handle attached to the iron,

Figure 2 a view of the handle detached—

And in which letter *a* is a handle; *b*, iron; *c*, steel spring; *d*, lever; *e*, connecting-rod; *f*, notch in upright, *g*; *g*, upright; *h*, bolt; *i*, fulerum-bolt; *j*, hind upright.

In making new irons, I cast the uprights, *g* and *j*, with *h* to the iron. I apply the handle to irons already cast, by removing original handle, and drilling the iron for insertion of uprights *g* and *j*, which I fasten in the iron by means of a thread cut on the ends and screwed into the iron, or by rivets, or by means of split and wedge in ends, driven into the iron.

I attach the steel spring *c* to the handle by means of bolt *h*, the lower end of which spring exactly fits in the notch *f*, in upright, *g*, and holds the handle in place.

On the forward bend of the handle I make two lips, between which, and lengthwise of the handle, I put the lever *d*, and fasten it with the bolt *i*, which passes through the lips and lever, and serves as a fulerum.

I connect the spring *c* and lever *d* by means of the connecting-rod *e*, which passes through the handle *a*.

I make the handle *a* bent, and with a shoulder upon each end, as shown in fig. 2. The upright, *j*, has a cavity behind, for the insertion of the handle, and the upright, *g*, is so made that the handle *a* will drop into it to below the notch *f*.

To attach the handle, I put one end into the cavity in upright, *j*, and press the forward end into the upright, *g*, where it is securely and firmly held by the spring *c* flying back into the notch *f*.

When I desire to heat the iron, I press lightly upon lever *d*, which draws the spring *c* from the notch *f*, and removes the handle, which prevents heating the handle, and thus obviates the necessity, inconvenience, and trouble of cooling the handle in water every time the iron is used, as always has to be done when using such irons having handles permanently attached.

What I claim as my invention, and desire to secure by Letters Patent, is—

The combination of the handle *a*, spring *c*, lever *d*, connecting-rod *e*, uprights *g* and *j*, with the iron, *b*, constructed and operating substantially as described, and for the purpose specified.

ROBERT W. TOWLE.
